CLAIM

The ornamental design for a strand material dispenser or the like, as shown and described.

DESCRIPTION

FIG. 1 is a front elevational view of a strand material dispenser or the like, showing my new design;

FIG. 2 is a left side elevational view thereof;

FIG. 3 is a right side elevational view thereof;

FIG. 4 is a top, plan view thereof;

FIG. 5 is a bottom plan view thereof;

FIG. 6 is a rear elevational view thereof;

FIG. 7 is a front perspective view thereof;

FIG. 8 is a rear perspective view thereof;

FIG. 9 is a front perspective view thereof in an exploded condition; and

FIG. 10 is a rear perspective view thereof in an exploded condition.
